UNITED STATES PATENT OFFICE.

ELON B. BUTTERFIELD, OF NEW YORK, N. Y.

IMPROVEMENT IN BREECH-LOADING ORDNANCE.

Specification forming part of Letters Patent No. 33,635, dated November 5, 1861.

To all whom it may concern:

Be it known that I, ELON B. BUTTERFIELD, of the city and county of New York, and State of New York, have invented certain new and useful Improvements in Breech-Loading Cannon; and I do hereby declare that the following is a full and correct description thereof, reference being had to the annexed drawings, making a part of this specification, and to the letters of reference thereon.

Figure 1 of the drawings represents a cut section of the breech of a cannon provided with my improvements; Fig. 2, a modification of the same; Fig. 3, a rear view with the breech-piece in place; Fig. 4, a rear view, with breech-piece thrown up to permit the entrance of the charge.

My invention consists in combining with the breech of a breech-loading cannon a movable breech-pin and a movable breech-piece, the breech-pin being arranged and constructed so as to screw into the end of the bore, and the breech-piece having a socket, in which also a screw is cut corresponding with and forming a continuation of the screw in the bore or chamber.

Letter *f* represents the movable breech-piece or cap; *g*, a pin screwed into the breech, on which the breech-piece turns; *h*, a stop against which the breech-piece rests when turned aside for the purpose of charging the piece; *i*, a lug projecting from the breech-piece, which takes against the upper horizontal surface of the bent lug or keeper *j*.

Letter *k* represents a socket in the breech-piece, in which is cut an internal screw corresponding with and forming a continuation of the screw in the breech at the end of the bore or chamber, when the breech-piece is in its proper place, for the purpose of introducing the breech-pin.

Letter *l* represents the movable breech-pin, on the periphery of which a screw is cut corresponding with the internal screws cut in the socket of the breech-piece and in the breech. The breech-pin is also provided with a shank, which extends back through a hole in the middle of the socket of the breech-piece, and has a hand-wheel attached to it.

Letter *m*, Fig. 1, and *n*, Fig. 2, represent square and conical shoulders or surfaces, against which the breech-pin takes by similar surfaces when screwed home.

Letter *o* represents a washer lying in the

bottom of the socket of the breech-piece. The washer should be of such a thickness that when the breech-pin is screwed back so that its front face will clear the breech the back shoulder will take against the washer, the momentum of the hand-wheel assisting the gunner very materially in raising the breech-piece, which, by thus gaging accurately the depth of the socket, is raised or begins to rise the instant the breech-pin is withdrawn sufficiently to be clear of the breech, the screw in the socket of the breech-piece being a continuation of the screw in the breech. The breech-pin is presented in a proper manner to enter the screw in the breech whenever the breech-piece is brought down to its proper place for that purpose.

Should it become necessary to abandon the piece on the field, the breech piece and pin may be removed by unscrewing the gin *g*; or, if preferred, the pin *g* may be made with a slot and split key in place of the screw-head.

The operation of parts is as follows, viz: The charge is introduced while the breech-piece is in position, as shown in Fig. 3, and the breech-pin run in by turning the hand-wheel until it takes against the shoulder *m* or *n*, the front face of the breech-pin jamming or ramming the charge home. To reload the piece the breech-pin is run back, by turning the hand-wheel, until its back shoulder comes against the washer at the bottom of the socket or breech-piece, when the breech-piece immediately rises by reason of the momentum of the wheel and the force applied, as before described.

What I claim as my invention and improvement in breech-loading cannon is—

Combining with the breech of a breech-loading cannon a movable breech-pin and a movable breech-piece, the breech-pin being arranged and constructed so as to screw into the breech at the end of the bore or chamber, and the breech-piece having a socket in which is a screw corresponding with and forming a continuation of the screw in the bore or chamber, substantially as and for the purposes described.

New York, September 11, 1861.

ELON B. BUTTERFIELD.
